UNITED STATES PATENT OFFICE.

WILLIAM A. VAN WINKLE, OF MIDLAND, MICHIGAN, ASSIGNOR TO THE DOW CHEMICAL COMPANY, OF MIDLAND, MICHIGAN, A CORPORATION OF MICHIGAN.

METHOD OF MAKING NOVOCAIN.

No Drawing.

Application filed March 31, 1920. Serial No. 370,280.

To all whom it may concern:

Be it known that I, WILLIAM A. VAN WINKLE, a citizen of the United States, and a resident of Midland, county of Midland, 5 and State of Michigan, have invented a new and useful Improvement in Methods of Making Novocaine, of which the following is a specification, the principle of the invention being herein explained and the best 10 mode in which I have contemplated applying that principle, so as to distinguish it from other inventions.

Various alkamine esters of para-amino-benzoic acid have come into use as local 15 anaesthetics, the most widely used and valuable one being the hydrochloride of the diethylamine derivative of ethyl para-aminobenzoate, known to the trade as novocaine or latterly as procaine, this compound 20 having the formula:

25 The preferred method of making novocaine as described in May's "Chemistry of Synthetic Drugs" (see p. 102) and in various 30 patents there cited involves the reduction of the intermediate product diethylaminoethyl ester of para-nitrobenzoic acid with tin and hydrochloric acid, as indicated by the following equation:

Without detailing various difficulties that 40 are encountered in carrying out this method of reduction, one of the principal being that the tin requires to be precipitated thereafter as by means of hydrogen sulphide and the removal of the resulting precipitate is annoying, I have found that such reduction 45 can be much more expeditiously and economically accomplished by electrolytic means.

The present invention then consists of the 50 steps hereinafter fully described and particularly pointed out in the claims, the following description setting forth but one of various ways in which the principle of the invention may be used.

The ester which constitutes the intermediate product above referred to is soluble 55

in water and accordingly readily lends itself to electrolytic treatment. In such treatment I preferably acidify the solution by adding a mineral acid, for example sulphuric acid, from ten to twelve per cent of said ester being added to a twenty-five per cent acid solution. I also preferably add a catalytic agent, for example stannous chloride, a small amount of such agent being sufficient. Thus in practice I employ not to exceed one-half of one per cent of such stannous chloride.

The anode used is preferably composed of sheet lead, while the cathode is of nickel, and a current having a potential of from 70 three to five volts is employed. The electrolysis should be carried on at ordinary room temperature whereupon the reduction proceeds easily and quickly, giving the desired amino-compound exactly as in the 75 equation above presented to illustrate the reaction where tin and hydrochloric acid are employed. The electrodes are unaffected by the reaction except that the tin plates out on the cathode, and oxide forms on the 80 anode, but neither is detrimental to operation.

A diaphragm of suitable acid-resistant material is of course interposed between such electrodes, the foregoing solution of 85 ester, acid and stannous chloride constituting the catholyte, while a dilute solution of a mineral acid, such as sulphuric acid, constitutes the anolyte.

Other modes of applying the principle of 90 my invention may be employed instead of the one explained, change being made as regards the method herein disclosed, provided the step or steps stated by any of the 95 following claims or the equivalent of such stated step or steps be employed.

I therefore particularly point out and distinctly claim as my invention:

1. In the manufacture of novocaine, the 100 method of reducing the intermediate diethylaminoethyl ester of para-nitrobenzoic acid, which consists in treating the same electrolytically, substantially as described.

2. In the manufacture of novocaine, the 105 method of reducing the intermediate diethylaminoethyl ester of para-nitrobenzoic acid, which consists in dissolving the same in acidulated water, and then passing an electric current therethrough.

3. In the manufacture of novocaine, the 110

method of reducing the intermediate diethylaminoethyl ester of para-nitrobenzoic acid, which consists in dissolving the same in acidulated water containing a small quantity of a suitable catalytic agent, and then passing an electric current therethrough.

4. In the manufacture of novocaine, the method of reducing the intermediate diethylaminoethyl ester of para-nitrobenzoic acid, which consists in dissolving the same in water containing approximately twenty-five per cent of sulphuric acid and a small quantity of stannous chloride, and then passing an electric current therethrough.

5. In the manufacture of novocaine, the method of reducing the intermediate diethylaminoethyl ester of para-nitrobenzoic acid, which consists in dissolving the same in approximately ten (10) parts of water containing approximately twenty-five per cent of sulphuric acid and not to exceed one half ($\frac{1}{2}$) of one per cent of stannous chloride, and then passing an electric current therethrough.

Signed by me at Midland, Michigan, this 26th day of March, 1920.

WILLIAM A. VAN WINKLE.
